FABRIC TREATING MACHINE

Harold H. Belcher, Philadelphia, Pa., assignor to
 The Philadelphia Drying Machinery Company,
 Philadelphia, Pa., a corporation of Pennsylvania

Application July 13, 1931, Serial No. 550,443

8 Claims. (Cl. 34—48)

My invention relates to machines useful in treating textile fabrics; and it has more particular reference to machines for performing operations such as drying, tentering, cooling, folding, etc., of freshly bleached or dyed fabrics in preparation for storage or shipment.

Considered in its broadest aspect, my invention is directed toward enabling the aforementioned and like operations to be effected continuously and economically in a minimum of time, and with assurance of consistent uniformity in appearance and feel of the treated fabric.

In connection with a machine suitable to the attainment of the foregoing desiderata, I aim to make provisions, in a drying chamber through which the fabric is guided over a succession of horizontal longitudinal passes, for circulating the air laterally or crosswise of the chamber over separate courses within as many definite superposed drying zones, so as to pass over and under, and to a certain extent through the runs of the fabric respectively within such zones; as well as provisions whereby different regulatable temperatures may be maintained within the several zones aforesaid to predetermine graduated drying of the fabric concurrently with progression of the latter in the machine.

Another object of my invention is to provide baffle means whereby the air circulated in each of the several drying zones is obstructed in certain of the spaces between the runs of the fabric thereby to set up a slight pressure differential between opposite sides of the said fabric runs, the pressure being so directed as to promote penetration of the fabric by the air and at the same time to assist in its retention by a tentering conveyor means which is relied upon to maintain it under transverse tension incident to progression in the machine.

40 A further object of my invention is to provide for constant proportionate replacement of the saturated air within the machine by fresh air from the exterior, with determination at the same time of a general flow of the air through the several zones in the drying chamber, in a direction contrary to the travel of the fabric.

Another object of my invention is to provide for the extraction of free moisture from the fabric previous to its entry into the drying chamber, with resultant shortening of the time period required for the drying operation; and also for cooling the fabric to the outside temperature as it emerges from the machine.

Still other objects and attendant advantages of this invention will be manifest from the follow-

ing detailed description considered in connection with the attached drawings, wherein Fig. I is a plan view of a fabric treating machine conveniently embodying the present improvements.

Fig. II is an illustration partly in side elevation and partly in longitudinal section viewed as indicated by the arrows II—II in Fig. I; and,

Fig. III shows a cross sectional view of the machine taken as indicated by the arrows III—III in Figs. I and II.

As herein depicted, my improved fabric treating machine comprises an elongate housing 5 with a built up skeleton frame 6 of structural iron; and with top, side and end walls 7, 8, 9, 10 and 11 of sheet metal supported by the said skeleton frame. In reality, the several walls 7—11 of the housing 5 are preferably constructed double with interposition of suitable thermo-insulation after standard practice in this art. At the forward or left hand end (as considered in Figs. I and II) of the machine, the skeleton frame 6 is extended beyond the housing 5 as at 12, to afford support for the various instrumentalities whereby the fabric F, which is being treated, is guided and longitudinally tensioned exteriorly of the housing 5. As shown, these guide instrumentalities include rollers 13, 14 and 15 (Fig. II) by which the fabric F is directed down the frontal side and beneath the tread boards of an operator's platform 16. After rounding the roller 15, the fabric F is trained over and under a pair of tension rods 17 and thence over a stationary spreader bar 18 by which all wrinkles and other irregularities are smoothed. From the spreader bar 18 the fabric F is passed over the longitudinally slotted horizontal tube 19 of a vacuum extractor 20 located at the forward end of the frame extension 12, for removal of the free moisture therefrom. As shown in Figs. I and II, the extractor tube 19 connects with a pipe 21 leading from a motor-driven suction blower 22 at one side of the machine. After leaving the extractor tube 19, the fabric F is trained about another fixed guide roll 23 and thereby directed to a drag drum 24. By cooperation with the drag drum 40

24, still another stationary guide roller 25 determines the formation of a drop loop L in the fabric F, which loop is supported, with provision of a definite amount of slack, by a spray 26, see Fig. II. From the roller 25, the fabric F is passed horizontally forward to a second tensioning device including a pair of guide rods 27 and a transverse tensioning bar 28 whereby it is maintained under a definite tension for presentation to a tentering conveyor which comprises a pair of 55

endless sprocket chains 29, 30. As shown in Fig. II, the chains 29, 30 are trained about a pair of sprocket wheels 31, 32 mounted on a transverse shaft 33 above the drag drum 24, see Fig. I. Upon 5 rounding the sprocket wheels 31, 32 the conveyor chains 29, 30 follow a divergent upward course to a pair of sprockets 34, 35 mounted on another transverse shaft 36 near the top of the framework extension 12, immediately adjacent the 10 frontal end wall 10 of the housing 5, see Figs. I and II. By these sprockets 34, 35, the chains 39, 40 and 41 are directed through a horizontal slot or opening 37 in the frontal wall 10 of the housing 5 into the interior of the said housing, 15 which affords an elongate drying chamber with a series of vertically spaced longitudinally-directed partitions 38, see Fig. III, which divide it into a number of superposed drying zones 39, 40 and 41. Within the enclosure the conveyor 20 chains 29, 30 are caused to trace a number of horizontal runs back and forth longitudinally of the machine in each of the drying zones 39, 40 and 41 successively, incident to progressing the fabric F through the machine, by transversely 25 spaced vertically arranged sprocket wheels 42, 43 and 44, 45 respectively at the opposite ends of the enclosure. From Figs. I and III it will be noted that the sprocket wheels 42, 43 are carried by a fixed portion 46 of the skeleton frame 6, while 30 the sprocket wheels 44, 45 are carried by a frame 47 supported on rollers 48 with capacity for adjustment transversely of the drying chamber. The means for adjusting the frame 47 include a 35 number of screws 49 which engage suitable nut bearings 50 on the frame and which are driven, through speed reduction gearing conventionally indicated at 51 in Fig. I, by an electric motor 52 arranged exteriorly of the machine at that side which is uppermost in Fig. I. The horizontal runs of the chains 29, 30 between the sprockets 42, 43 and 44, 45 are supported in guideways 53, 54 respectively secured to the portion 46 of the skeleton frame 6 and to the adjustable frame 47; and the links of the said chains are fitted 45 with pins 55, 56 upon which the edges of the fabric F are impaled. It will be particularly noted from Fig. III that the pins 55, 56 of the two conveyor chains 29 and 30 are respectively inclined outwards or in a direction away from each other. 50

The lowermost pair of sprocket wheels of the series 43, 45 are mounted on a shaft 57 (Figs. I and II) having journal bearing in the fixed and adjustable frames 6 and 46, which shaft 57 is driven by a speed reducing spur gear train 58 55 from a power shaft 59 at the right hand end of the machine. The power shaft 59 derives motion, through a sprocket chain connection 60, from an adjustable variable speed device 61 mounted on the top of the housing 5. This variable speed device 61 may be of any suitable commercial type, it being driven, in turn, by a sprocket chain or belt connection 62 from a juxtaposed motor 63 also mounted on the top of the housing 5. By means of a suitable train of 60 spur gears, not shown, motion is communicated from the shaft 57 to all the shafts of the several conveyor chain sprockets 43. The drag drum 24 previously referred to is co-ordinated, by means of a sprocket chain 64, with another adjustable 65 variable speed device 65 supported by a shelf 66 in the external prolongation 12 of the frame 6, see Fig. II. The device 65 in turn derives motion, through a chain 67, from the conveyor sprocket shaft 33. Obviously, by adjusting the variable speed device 61, the conveyor may be made to

travel at any desired rate of speed; while, by adjusting the variable speed device 65, a proportionate differential speed may be determined for the drag roller 24 to maintain the desired amount of slack of the fabric F within the 5 scray 26.

Referring again to Fig. III, it will be noted that the horizontal partitions 38 extend only part-way or approximately half-way across the drying chamber within the enclosure 5, and also that 10 the said partitions terminate short of the left hand side wall 8 of the housing 5. By virtue of this construction, the superimposed drying zones 39, 40 and 41 are intercommunicative to a limited extent at the left of the partitions 38 as and 15 for a purpose which will be later on explained, as well as more freely to the right of said partitions 38. There is also a supplemental partition or baffle 70 near the roof 7 of the housing which, like the horizontal partitions 38, does not extend 20 the full width of the drying chamber, but which does reach to the side wall 8. The purpose of this supplemental partition 70 will also be later on explained.

Along the side of the machine that is lowermost 25 in Fig. I, the housing 5 is formed with a pair of offsets or bays 71. Horizontal partitions 72, extending between the fixed portion 46 of the frame 6 and the side wall 9 of the housing 5 set 30 apart in the offsets 71 a number of superposed heating compartments 73, 74 and 75, respectively, at the levels of the zones 39, 40 and 41 within the drying chamber of the housing 5, see Fig. III. As shown, these heating compartments 73, 74 and 75 are similarly constructed, each being subdivided by a horizontal partition 76 into upper and lower subdivisions 77, 78 which communicate laterally with the upper and lower portions of the drying zones 39, 40 and 41, respectively, above and below the fabric runs marked F in Fig. III. 40 Thus the subdivision of the compartments 73, 74, 75 corresponds to these fabric runs F. Within the subdivisions 77, 78 of the respective heating compartments 73, 74 and 75 are steam heating coils 79 and 80, provided with separately regulatable valves 81 (Fig. I). In each instance, a series of coaxial centrifugal fans 82 operate to maintain a circulation and recirculation of air laterally of the corresponding drying zone, with transverse passes in opposite directions back and forth 50 in contact with opposite sides of the fabric run marked F in Fig. III, in the top and bottom of the zone. In the transverse circuits of the adjacent zones the air flow is relatively reversed. The fans 82 in the heating compartments 73 and 75, it 55 will be noted from Fig. III, are arranged to draw air in from the lower portions of the drying zones 39 and 41 through the heating compartment subdivisions 78 past the heating coils 80 in the latter, and to discharge the air back into the upper portions of the said drying zones 39 and 41 via the upper subdivisions 77 past the coils 79. The fans 82 in the intermediate heating compartment 74, on the other hand, maintain air circulation 60 in a reverse direction; that is to say, they operate to draw the air from the upper part of the intermediate drying zone 40 into the upper subdivision 77 of the said heating compartment 74 past the coils 79 therein, and to discharge it back into the lower part of the said intermediate drying zone 40 through the lower subdivision 78 of the compartment 74 past the heating coils 80 therein. By action of the several fans 82, it is evident that the circulated air is caused to flow 65 over and under the runs of the fabric F in the 70 75

respective drying compartments 39, 40 and 41, the reversed action of the fans in the intermediate drying compartment being advantageous in preventing undesirable mixing of the air between the contiguously inter-communicating passes of adjoining drying zones, through determination of parallel flow of the air streams at opposite sides of the partitions 38 in the same direction, as will be manifest from Fig. III.

10 In order to secure penetration of the fabric to a certain extent by the air circulated in the several drying zones 39, 40 and 41, we provide two vertical series of baffles or dampers 83 and 84 which are supported by the frames 6 and 46 with 15 in the housing 5. These baffles 83 and 84, it will be noted from Fig. III, serve to partially obstruct the flow of the air in alternate spaces between the runs of the fabric F. As a consequence, slightly different pressures are set up 20 between opposite sides of the several horizontal runs of the fabric F, which, in tending to equalize, cause flow of the air through the fabric as indicated by the arrows in Fig. III. It will also be remarked from Fig. III that the higher of the 25 two pressures acts, in each instance, to assist retention of the fabric runs by the pins 55 on the tentering conveyor chains 29, 30. The air is thus in part blown through the fabric F for intimate contact with its fibers, and in part blown across 30 opposite sides of the several fabric runs with attendant acceleration of the drying action.

Referring to Figs. I and II, the fans 82 are grouped in aligned pairs, which pairs are enclosed in separate housings or bays set apart as 35 a consequence of the central recessing of the offsets or bays 71 as at 85, 85. The fan drive shafts 86 extend out through the opposite transverse walls of all the bays. The contiguous ends of the shafts 86 of the aligned pairs of the fans 82 40 are connected within the recesses 85 of the housing offsets 71 as well as in the space 71a between the said offsets, by flexible couplings 88. The recessed construction of the offsets 71 is further advantageous in that it permits location 45 of all the fan shaft bearings 87 at the exterior of the housing 5 where they are readily accessible for oiling and kept cool. As shown in Fig. I, each horizontal series of the fans 82 is driven by a separate exteriorly located motor 89. Access 50 is had to the coils 79 and 80 within the various drying compartments 73, 74 and 75 by means of full height doors 90 at opposite ends of the housing offsets 71.

In order to constantly replace the spent moisture laden air within the drying chamber by 55 fresh air from the exterior I have made provisions as follows:—Mounted on the top of the housing 5 adjacent the side wall 8 and near opposite ends of the housing are centrifugal suction blowers 91 which are driven by separate electric 60 motors 92 and serve to draw out a definite proportion of the air through discharge openings in the top 7 of the housing. In this connection, it will be observed that the supplemental baffle 70 65 previously referred to prevents short circuiting of the air thus drawn from the uppermost drying zone 39 by the exhaust blowers 91, and, furthermore, operates to insure passage of most of the air over the top of the wettest run of the 70 cloth to extract the moisture from the latter to a maximum extent before being exhausted by the blowers 91. The action of the blowers 91 is satisfied by fresh air entering the lowermost drying zone 41 from the exterior, through a pair 75 of preheaters 93 at one side of the housing 5,

the said preheaters being open to the outside atmosphere and containing steam coils 94 for warming the incoming air. Under the action of the blowers 91, and the influence of the inward and downward sloping deflector baffle(s) 94a extending along the wall 8 above the air inlet opening(s) from the preheaters 93 (Fig. III) the incoming air is obliged to mingle first with the dryest air in the lowermost drying zone 41, and a gradual upward robbing or transmission of air will take place from zone to zone amongst the several drying zones 39—41, around the opposite edges of the horizontal partitions 38, in a generally upward direction contrary to the general downward movement of the fabric F as indicated by the dotted arrows in Fig. III.

After having passed through the whole of the drying chamber, the fabric F emerges through an opening 95 in the lower part of the front wall 10 of the latter, and, in this instance, enters a 20 supplemental chamber 96 in which it is cooled. Within the cooling chamber 96 is a pair of sprocket wheels 97, 98 for the conveyor chains 29, 30, which are mounted on a transverse shaft 99. From these sprockets 97, 98 the chains 25 travel vertically and out through an opening in the top of the cooling chamber 96 to idler sprockets 100 suitably journaled in the forward extension 12 of the framework 6, whereby the said chains are directed to the feed sprockets 31 and 30 32. Immediately upon entering the cooling chamber 96, the fabric F is withdrawn from the conveyor chains 29, 30 and caused to trace a number of runs up and down within said chamber under the guidance of freely revolving transverse rollers 101. The cool air entering at the top of the chamber 96 passes downward through the runs of the fabric F and enters the drying enclosure through the opening 95, thereby supplementing the fresh air taken in through the 40 preheaters 93. Suitable means, not shown, may be provided in the chamber 96 for circulating the air to hasten the cooling. After having traversed the cooling chamber 96, the fabric leaves the top of the latter through an opening 102, and is 45 thereafter directed, by another guide roller 103, to a folding mechanism 104 suspended within the external extension 12 of the machine frame 6. This folding mechanism 104 is of a type comprising a pair of draw rolls 105 which are driven 50 through the medium of a chain connection 106 with one of the conveyor sprockets 33 and a slowly oscillating guide 107 which delivers the fabric F in horizontal folds.

The various novel features herein disclosed all 55 contribute toward attainment of greater perfection in the construction as well as in the operation of machinery for treating textile fabrics. The facilities provided for maintaining differential temperatures in as many different zones of 60 the drying chamber, and for maintaining air circulation in opposite directions in alternate of the aforesaid zones, are especially unique, and make it possible to uniformly dry continuous lengths of fabric F in a minimum of time. The 65 machine of my invention is well adapted to the treatment of fine fabrics, including worsteds, where the matter of temperatures is exceedingly important to ultimately insure a satisfactory finish and feel. The machine may of course be 70 constructed without a vacuum extractor and the cooling chamber, these adjuncts are not especially essential or advantageous in the treatment of certain fabrics.

Having thus described my invention, I claim: 75

1. A machine for drying fabrics in lengths comprising an elongated housing affording a plurality of superposed contiguously intercommunicating drying zones; means for directing fabric in longitudinal horizontal runs through the several drying zones; and means coating with the fabric runs to circulate and recirculate the air in transverse circuits back and forth across the several drying zones, with passes of the air oppositely in the top and bottom of each zone in contact with opposite sides of a run of fabric therein, and with reverse air flow in the circuits of adjacent zones, so that the flow in the intercommunicating contiguous passes of adjacent zones is in the same direction.

2. A machine for drying fabrics in lengths comprising an elongated housing; means for directing fabric therethrough in a multiplicity of longitudinal horizontal runs which occupy only part of the width of the housing and have their edges spaced inward from both its sides; horizontal longitudinal partitions in said housing defining a plurality of superposed contiguously intercommunicating drying zones, such partitions dividing the space between one side of the housing and the adjacent edges of the fabric runs into superposed chambers corresponding to the drying zones; and means in said chambers for circulating and recirculating the air in transverse circuits back and forth across the several drying zones, with transverse passes of the air oppositely in the top and bottom of each zone in contact with opposite sides of a run of fabric therein, and with reverse air flow in the circuits of adjacent zones.

3. A machine for drying fabrics in lengths comprising an elongated housing affording a plurality of superposed contiguously intercommunicating drying zones; means for directing fabric in longitudinal horizontal runs through the several drying zones; and means for circulating and recirculating the air in transverse circuits back and forth across the several drying zones, with passes of the air oppositely in the top and bottom of each zone in contact with opposite sides of a run of fabric therein; said last-mentioned means comprising a series of superposed compartments in the housing alongside the fabric runs, each opening into the corresponding drying zone above and below the aforesaid run of fabric in said zone, and correspondingly subdivided into upper and lower subdivisions, and centrifugal air circulating fans in said compartments drawing air from one subdivision of each and delivering into its other subdivision, the delivery of air from the fans being reversed as between those in adjacent compartments, so that the air flow in the intercommunicating contiguous passes of adjacent zones is in the same direction.

4. A machine for drying fabrics in lengths comprising an elongated housing; means for directing fabric therethrough in a multiplicity of longitudinal horizontal runs which occupy only part of the width of the housing and have their edges spaced inward from both its sides; horizontal longitudinal partitions in said housing defining a plurality of superposed drying zones, such partitions extending inward from one side of the housing across the space between such side and the adjacent fabric edges, thus dividing this space into superposed chambers corresponding to the drying zones, and at the other side of the housing extending partly across the fabric runs but leaving the drying zones in commun-

cation adjacent the corresponding housing wall, as well as adjacent said chambers; and means in said chambers for circulating and recirculating the air in transverse circuits back and forth across the several drying zones, with transverse passes of the air oppositely in the top and bottom of each zone, and with reverse air flow in the circuits of adjacent zones.

5. A machine for drying fabrics in lengths comprising an elongated housing, with a side wall thereof recessed or offset inward at intervals, forming spaced bays; means for directing fabric through the housing in a multiplicity of longitudinal horizontal runs which occupy only part of the width of the housing and have their edges spaced inward from both its sides; horizontal longitudinal partitions in said housing defining a plurality of superposed drying zones, such partitions extending inward from the bayed side of the housing across the space between such side and the adjacent fabric edges, thus dividing this space into superposed chambers corresponding to the drying zones, and at the other side of the housing extending partly across the fabric runs, leaving the drying zones contiguously inter-communicating; means including air circulating fans in said chambers for circulating and recirculating the air in transverse circuits back and forth across the several drying zones, with transverse passes of the air oppositely in the top and bottom of each zone, and with reverse air flow in the circuits of adjacent zones, said fans having longitudinal drive shafts extending out through the opposed transversely extending walls of each of said bays, with bearings therefor accessible outside said transverse walls; and heating means for the air in said chambers, between said fans and said drying zones.

6. A machine for drying fabrics in lengths comprising an elongated housing with horizontal longitudinal partitions defining therein a plurality of superposed drying zones intercommunicating to a limited extent at one side of the housing, and also intercommunicating contiguously and more freely near its other side; means for directing fabric in longitudinal runs through the several drying zones; means at said other side of the housing for circulating and recirculating the air in transverse circuits back and forth across the several drying zones, with transverse passes of the air oppositely in the top and bottom of each zone in contact with opposite sides of a run of fabric therein; means for supplying outside air to the lowermost drying zone, to mingle with the transverse circulation therein; means for discharging air from the upper transverse pass of the uppermost drying zone; and a baffle in the upper pass of the uppermost drying zone extending from the housing side opposite its circulating means past said discharging means, so as to prevent short-circuiting of air from lower transverse passes to said exhausting means.

7. A machine for drying fabrics in lengths comprising an elongated housing; means for directing fabric therethrough in a multiplicity of longitudinal horizontal runs which occupy only part of the width of the housing and have their edges spaced inward from both its sides; horizontal longitudinal partitions in said housing defining a plurality of superposed drying zones, such partitions extending inward from one side of the housing across the space between such side and the adjacent fabric edges, thus dividing this space into superposed chambers corresponding to the

drying zones, and at the other side of the housing extending partly across the fabric runs but leaving the drying zones in communication adjacent the corresponding housing wall, as well as 5 adjacent said chambers; means in said chambers for circulating and recirculating the air in transverse circuits back and forth across the several drying zones, with transverse passes of the air oppositely in the top and bottom of each 10 zone, and with reverse air flow in the circuits of adjacent zones; means for supplying outside air to the lower transverse pass of the lowermost drying zone; means for discharging air from the upper transverse pass of the uppermost drying 15 zone; and a baffle in said upper pass of the uppermost drying zone extending from the side of the housing opposite said chambers inward past said discharging means, so as to prevent short-circuiting of air from lower drying zones directly to 20 said discharging means.

8. In a machine for drying fabrics in continuous lengths, an elongated drying chamber subdivided into a number of superposed drying zones

by longitudinal partitions extending approximately half-way across and terminating short of one longitudinal side wall of said chamber; a supplemental partition in the upper drying zone arranged to define an exhaust air chamber, and 5 effective to prevent short circuiting of air circulation through the drying chamber; guide means causing the fabric to trace a number of horizontal passes sinuously back and forth longitudinally above and below all of the partitions 10 in the drying chamber; separately enclosed vertically-rotating centrifugal fans, arranged in series at intervals along the length of the machine at one side, some of said fans being adapted to circulate air transversely of the drying chamber 15 in one direction and intervening fans circulating the air in a counter-direction, the shafts of the several fans being aligned and coupled exteriorly in the intervals between the fan enclosures; and exteriorly located means for driving 20 the said series of fans.

HAROLD H. BELCHER.
